DISCRIMINATING SIGNALING APPARATUS

Original Filed Dec. 3, 1923

—Inventor—
John E. Ostline

Chas. M. Landy Atty:

UNITED STATES PATENT OFFICE.

JOHN E. OSTLINE, OF LIVERPOOL, ENGLAND, ASSIGNOR, BY MESNE ASSIGNMENTS, TO AUTOMATIC ELECTRIC INC., OF CHICAGO, ILLINOIS, A CORPORATION OF DELAWARE.

DISCRIMINATING SIGNALING APPARATUS.

Application filed December 3, 1923, Serial No. 678,111. Renewed August 3, 1927.

This invention relates in general to discriminating signaling apparatus for automatic telephone systems, in which local subscribers call the special service operators for the purpose of initiating long distance, toll, or suburban calls, and is a further development of the invention shown in my prior application, Patent No. 1,612,045, filed May 14, 1923. More specifically, the broad general object of the present invention is to provide a tandem repeater for use in multi-office systems where the special service operators are called over tandem trunks.

When repeaters of the improved type disclosed herein are used, the associated trunks may be used for ordinary subscriber to subscriber service between offices, and may be used also for completing calls to the toll recording operator or to any other operator who may have reason to ascertain the class to which the calling substation belongs.

Specifically, any kind of calls, regardless of their nature, may be trunked over a common group of trunks to a distant tandem office at which they are split up by a selector, and are completed over the proper routes according to their destination, the improved tandem repeaters operating as an ordinary repeater, except when the call is extended to an operator who must be informed of the class to which the calling substation belongs, in which case means becomes effective to relay the characteristic test indication past the inductive connections in the repeater.

To accomplish the foregoing and other useful ends this invention comprises means which will be fully described in the specification which is to follow, reference being had to the accompanying drawing, which shows diagrammatically the apparatus and circuits involved in a complete connection between a calling subscriber at substation A and a trunk line extending to a special service operator's position M, by way of line switch C, selector E, tandem repeater TR, selector F, and the outgoing special service repeater R.

The substations A and A¹ are connected in bridge of a single pair of talking conductors and may be of any approved induction coil automatic type. As represented herein, substation A comprises essentially the receiver 1, switchhook 2, calling device 3, transmitter

5, induction coil 6, restricted service attachment S, condenser 9, and bell 10.

The restricted service attachment S comprises essentially the following: Spring 14, to which is fastened the iron member 8, and which has a contact point in its end; spring 7 which has a contact point in its end, and supporting member or bracket 11 which may be mounted on the terminal block in the bell box, as in this case, or other convenient points so long as operation of the attachment is not hindered. Springs 14 and 7 and supporting member 11 are assembled by means of various washers, insulators and screws 13. The adjusting screw 12 is used to secure the proper tension in spring 14, thus permitting it to operate only under certain conditions.

The line conductors 21 and 22 of the substations A and A¹ are connected at the central office to the individual line switch C, which is mechanically of the rotary type in which the wipers have no normal position and move in a forward direction only.

Line switch C has access to a plurality of trunk lines extending to selector switches, one of which is shown in outline at E, which are mechanically of the well known vertical and rotary type in which the bank contacts are arranged in horizontal rows or levels.

The selector E has access on one level to a group of outgoing trunks, one of which is the trunk associated with the tandem repeater TR. This trunk extends to a distant tandem office and terminates there in the second selector F.

The selector F, together with other selectors (not shown), has access on one level to a group of special service trunks, one of which is the trunk associated with the outgoing special service repeater R.

The trunk associated with the special service repeater R comprises conductors 211 and 212 and terminates at a toll recording operator's position in the terminating equipment M.

The tandem repeater TR consists essentially of a plurality of relays, a repeating coil RC, and an individual signal lamp L³, together with suitable circuits for performing the necessary functions, as will be pointed out hereinafter. Battery B³ is preferably common to a group of tandem repeaters such as TR.

The outgoing special service repeater R extends them by way of wipers 31 and 33, bank contacts 34 and 36, and the associated line conductors to the windings of the line relay of selector E. The line and release relays (not shown) of the selector E now energize and prepare the switch for operation in the usual well known manner.

The terminating equipment M at the special service operator's position consists essentially of the polarized relay 201, different colored signal lamps L¹ and L², and a key K. An operator's simple and well known head set circuit is also shown diagrammatically at O.

A brief description of the apparatus having been given the operation of the same will now be explained more in detail. For this purpose it will be assumed that the subscriber at substation A, which subscriber it will be further assumed is to be denied special (toll) service, desires to call a special service (recording) operator O in order to place a long distance, toll, or suburban call, as the case may be. In order to do this, the subscriber at substation A removes his receiver and then dials the operator's number.

When the receiver is removed at substation A, line relay 24 energizes over line conductors 21 and 22, but the primary winding of the induction coil at the substation, in series with the line relay, being marginally adjusted, is not energized sufficiently to attract armature 8. Upon energizing, line relay 24 places ground on private normal conductor 40 at armature 29, thereby making the calling line busy, and closes a circuit for switching relay 23 and stepping magnet 25 in series. As a further result of the energization of line relay 24, it connects test wiper 32 to the junction of switching relay 23 and stepping magnet 25 at armature 30.

In case the trunk upon which the wipers of the line switch are standing is idle, switching relay 23 energizes immediately. Assuming the trunk to be busy, however, switching relay 23 is short circuited by ground encountered on the busy test contact by test wiper 32 and does not energize, and the wipers are rotated step by step by the buzzer-like action of stepping magnet 25, which operates through test wiper 32. When an idle trunk is reached, which trunk it will be assumed is the one terminating in bank contacts 34, 35 and 36, switching relay 23, being no longer short circuited, energizes in series with stepping magnet 25. Stepping magnet 25, however, does not energize at this time on account of the high resistance of switching relay 23. Switching relay 23, upon energizing, opens a point in the test circuit and prepares the holding circuit at armature 27, and at armatures 26 and 28 disconnects line conductors 21 and 22 from the winding of line relay 24 and ground, and

When the calling subscriber A operates his calling devices in accordance with the first digit in the special service (recording) operator's number, the selector E raises its wipers 41, 42 and 43 opposite the corresponding level of bank contacts and then selects an idle trunk in the usual and well known manner. It will be assumed that the trunk selected at this time is the one extending to tandem repeater TR, indicated as 51, 52 and 53. That being the case, line relays 62 and 63 of the tandem repeater TR energize over the calling line, the latter disconnecting armature 69 from ground, while the former closes a circuit at armature 68 for release relay 64. Release relay 64, upon energizing, places ground on release trunk conductor 52 at armature 70, thereby closing the usual holding circuit for the preceding switches E and C.

As a further result of the energization of line relay 62, it completes a bridge across the associated outgoing trunk conductors at armature 67. This bridge includes the right hand repeating coil windings and the marginally adjusted relay 61. Responsive to the closure of this bridge, the line and release relays (not shown) of the selector F energize and prepare the switch for operation in the usual manner. Relay 61, in the repeater R, however, is not energized at this time on account of its marginal adjustment.

When the calling subscriber at substation A manipulates his calling device in accordance with the second and last digit in the desired number, line relay 62 of the repeater TR is deenergized a corresponding number of times. Each time line relay 62 deenergizes, it opens the bridge across the associated trunk conductors at armature 67, resulting in a momentary deenergization of the line relay (not shown) of the selector F. Accordingly, the selector F is operated to raise its wipers to the desired level and to select an idle trunk. In this case, it will be assumed that the trunk extending to the outgoing special service repeater R is the one selected. Accordingly, line relays 101 and 104 of the repeater R energize over the loop which extends back and includes the back bridge of the repeater TR. Relay 101, upon energizing, closes a circuit at armature 114 for relay 103 by way of armature 118 and its resting contact, and at armatures 111 and 112 prepares a circuit over which battery B is subsequently connected in series with the exchange battery. Battery B is short circuited through the in-

dividual trunk lamp L for the time being, however, at armatures 116 and 121. Relay 103, upon energizing, places ground on the associated release trunk conductor at its upper armature 120; opens one point in the short circuit of battery B at armature 121; and closes a circuit at armature 122 for relay 102 by way of the working contact of armature 113 and said armature. Relay 102, upon energizing, places a multiple ground on the release trunk conductor at its upper armature 115; locks itself up at armature 117; opens at armature 118 the circuit for relay 103; and opens at armature 116 the short circuit of battery B. Pending the deenergization of relay 103, battery B is connected in the line circuit in series with the exchange battery over the following path: From ground by way of relay 104, trunk line conductor 99, lower wiper of the selector F, lower right-hand winding of repeating coil RC, marginal relay 61, upper right-hand winding of the repeating coil RC, working contact of armature 67 and said armature, upper wiper of the selector F, trunk line conductor 97, armature 125 and its resting contact, armature 111 and its working contact, signal lamp L, battery B, working contact of armature 112 and said armature, armature 126 and its resting contact, and relay 101 to grounded battery. These batteries in series energize relay 61 sufficiently to operate its armature, thereby preparing a circuit at armature 66 for shorting out relay 104, and closing at armature 65 a circuit to include signal lamp L² and battery B³ before opening the circuit including the exchange battery. Battery B³ energizes the induction coil 6 (substation A) sufficiently to operate armature 8 of the restricted service attachment, which armature, as before mentioned, is tensioned against operating on the normal operating current. Armature 8 places ground on the line circuit by way of the working contact of spring 7 and shorts out relay 63. Relay 63, upon deenergizing, connects armature 69 with ground and shorts out relay 104 of outgoing special service repeater R.

Relay 104, upon deenergizing, closes a circuit at armature 124 for relay 106 as follows: Ground, working contact of armature 114 and said armature, armature 118 and its working contact, armature 123 and its working contact (relay 103 being slow acting holds up sufficiently long to complete this circuit), armature 124 and its resting contact, relay 106 to grounded battery. Relay 106, upon energizing, locks itself up at armature 130 by way of ground, working contact of armature 119 and said armature, and reverses the direction of signaling current to be applied to the selected trunk line, at armatures 129 and 131. Relay 103, upon finally deenergizing, again closes at armature

121 the local short circuit of battery B, and closes a circuit at armature 123 for relay 105 by way of ground, working contact of armature 114 and said armature, and armature 118 and its working contact. Relay 105 accordingly energizes with results to be explained hereinafter.

The short circuiting of battery B, referred to above, allows armatures 65 and 66 of relay 61 to fall back, thus replacing battery B³ with the normal exchange battery at armature 65, and removing the ground connection from the trunk conductor 99 at armature 66, allowing line relay 104 of the repeater R to energize again. The replacing of battery B³ with the normal exchange battery allows armature 8 of the restricted service attachment at the calling substation A to fall back, thus removing the ground or short from the line circuit and allowing line relay 63 of the repeater TR to reenergize.

In the repeater R, relay 105, upon energizing as above pointed out, opens at armatures 125 and 126 both sides of the test battery B circuit; and closes at armatures 127 and 128 the signaling current circuit as follows: ground, right-hand winding of impedance coil 107, working contact of armature 131 and said armature, working contact of armature 128 and said armature, trunk conductor 212, polarized relay 201, trunk conductor 211, armature 127 and its working contact, armature 129 and its working contact, left-hand winding of impedance coil 107 to grounded battery. Polarized relay 201 energizes over this circuit and actuates its armature 203 in the proper direction to close a circuit for red lamp L² by way of key K. Red lamp L², upon lighting, notifies the operator of the call and that the substation is a restricted service (no toll) substation.

At an unrestricted substation no attachment is used. Consequently, when such a substation makes a call no ground will be picked up at an armature such as 8 to short out line relay 63, and in turn to short out line relay 104 and close a circuit for relay 106. Signaling current will therefore be applied over the following circuit: ground, right-hand winding of impedance coil 107, resting contact of armature 129 and said armature, working contact of armature 127 and said armature, trunk conductor 211, polarized relay 201, trunk conductor 212, armature 128 and its working contact, armature 131 and its resting contact, left-hand winding of impedance coil 107 to grounded battery. Polarized relay 201, upon energizing, operates its armature 203 in the proper direction to close a circuit for white lamp L¹ by way of key K. White lamp L¹, upon lighting, notifies the operator of the call and that the calling substation is an unrestricted service substation.

Upon the operator receiving either the red or white signal, depending on the class of substation calling, she bridges her head set O across the trunk conductors 211 and 212 by means of the key K, thus permitting conversation between her and the calling subscriber, and extinguishing the signal lamp. Upon learning the calling subscriber's desired number or call, she either makes a ticket on the call or denies the service as the case may require in the usual well known manner.

When the conversation is terminated the calling subscriber replaces his receiver, bringing about the disconnection of the apparatus in the usual manner. Briefly, upon the de-energization of the line relays 62 and 63 of tandem repeater TR, relay 64 deenergizes and removes ground from release trunk conductor 52 at armature 70, whereupon selector E and line switch C are released in the usual manner. Relay 62 also opens the bridge at armature 67, whereupon line relays 101 and 104 of outgoing special service repeater R deenergize. Release relay 102 deenergizes responsive to the retraction of armature 114 and breaks the circuit at armature 119 for relay 106 and opens the circuit of relay 105 at armature 118. Relay 105 thereupon deenergizes and disconnects the signaling current from the trunk circuit. As a further result of the deenergization of release relay 102, it removes ground from the associated release trunk conductor at armature 115, whereupon the selector F is released. All the apparatus has now been restored to normal.

In order to enable the present invention to be understood without any undue complications, the tandem repeater TR has been shown as a simple repeater having no means for reversing the direction of current flow in the associated trunk. It will be understood, however, that since the signal control through the repeater is accomplished by booster current and is independent of the direction of the current flow, the invention can readily be applied to repeaters of the reversing type where such repeaters are necessary.

Having described my invention, what I consider to be new and desire to have protected by Letters Patent will be pointed out in the appended claims.

What I claim is:

1. The combination, with restricted and unrestricted subscribers' stations, said restricted stations having an attachment placed on the induction coil, of a tandem repeater, of an outgoing special service repeater, means whereby any subscriber can extend connection to said tandem repeater, means whereby said tandem repeater can extend the connection to said outgoing special service repeater and thence to an operator's

position, means whereby said outgoing special service repeater causes said tandem repeater to test for the presence of said attachment, and means whereby said attachment causes said tandem repeater to cause said outgoing special service repeater to reverse the direction of signaling current and give the operator a characteristic signal indicative of the class of station.

2. In a telephone system, party lines, a plurality of stations on said lines divided into classes in accordance with the kind of service to which they are entitled, a tandem repeater, an outgoing special service repeater, means for extending any line when calling to said tandem repeater and thence to said outgoing special service repeater and an associated operator's position, and automatic means for informing the operator of the class to which the calling station belongs.

3. In a telephone system, a plurality of subscribers' stations some of which have restricted service attachments, a tandem repeater, an outgoing special service repeater, means whereby any of said subscribers' stations can extend a connection by way of said repeaters to an operator's position, and automatic means controlled by said attachments whereby said repeaters give the operator a characteristic signal without the knowledge of the calling subscriber when the calling station is a restricted service station.

4. In a telephone system, subscribers' lines divided into classes, a trunk extending to an operator's switchboard, means including automatic switches for extending any calling line to said switchboard, devices at the substations of lines belonging to a particular class, means associated with said trunk line for controlling said devices over established connections, signaling equipment in said trunk line controlled over established connections by said devices, inductive connections in such established connections, and means for relaying the characteristic circuit conditions necessary to accomplish the control of said devices and equipment past said inductive connections.

5. In a telephone system, a restricted service line, a trunk line extending to an operator's switchboard, means including a plurality of automatic switches and a repeater for connecting said line and trunk line, means associated with said trunk line for establishing a test circuit over that portion of the connection which extends back to said repeater, means in said repeater controlled over said test circuit for establishing a second test circuit including said first line, a device at the station on said first line controlled over said second test circuit to alter the circuit condition in the line, means in the repeater responsive to said altered circuit condition, and signaling equipment con-

trolled by said last mentioned means to advise the operator of the character of the connected line.

6. In a telephone system, party lines, a plurality of stations on said lines divided into classes in accordance with the kind of service to which they are entitled, a tandem repeater, an outgoing special service repeater, means for extending any line when calling to said tandem repeater and thence to said outgoing repeater and an associated operator's position, a booster battery associated with said outgoing repeater, means for temporarily connecting said battery to the line at said outgoing repeater, and means responsive to said connection for causing said tandem repeater to test the class of station calling.

7. In a telephone system, party lines, a plurality of stations on said lines divided into classes in accordance with the kind of service to which they are entitled, a tandem repeater, an outgoing special service repeater, means for extending any line when calling to said tandem repeater and thence to said outgoing repeater and an associated operator's position, a booster battery associated with said outgoing repeater, means for temporarily connecting said battery to the line at said outgoing repeater, means responsive to said connection for causing said tandem repeater to test the class of station calling, and means for informing the operator of the call and the class to which the calling station belongs.

8. In a telephone system, party lines, a plurality of stations on said lines divided into classes in accordance with the kind of service to which they are entitled, a tandem repeater, an outgoing special service repeater, means for extending any line when calling to said tandem repeater and thence to said outgoing repeater and an associated operator's position, a booster battery associated with said outgoing repeater, means for temporarily connecting said battery to the line at said outgoing repeater, a marginal relay in said tandem repeater, said relay operative responsive to the connection of said battery, and means responsive to the operation of said relay for testing the class of station calling.

9. In a telephone system, party lines, a plurality of stations on said lines divided into classes in accordance with the kind of service to which they are entitled, a tandem repeater, an outgoing special service repeater, means for extending any line when calling to said tandem repeater and thence to said outgoing repeater and an associated operator's position, a booster battery associated with said outgoing repeater, means for temporarily connecting said battery to the line at said outgoing repeater, a marginal

relay in said tandem repeater, said relay operative responsive to the connection of said battery, means responsive to the operation of said relay for testing the class of station calling, and means for informing the operator of the call and the class to which the calling station belongs.

10. In a telephone system, party lines, a plurality of stations on said lines divided into classes in accordance with the kind of service to which they are entitled, a tandem repeater, an outgoing special service repeater, means for extending any line when calling to said tandem repeater and thence to said outgoing repeater and an associated operator's position, a booster battery associated with said outgoing repeater, means for temporarily connecting said battery to the line at said outgoing repeater, a marginal relay in said tandem repeater, said relay operative responsive to the connection of said battery, a booster battery associated with said tandem repeater, and means controlled by said relay for connecting said second battery for testing the class of station calling.

11. In a telephone system, party lines, a plurality of stations on said lines divided into classes in accordance with the kind of service to which they are entitled, a tandem repeater, an outgoing special service repeater, means for extending any line when calling to said tandem repeater and thence to said outgoing repeater and an associated operator's position, a booster battery associated with said outgoing repeater, means for temporarily connecting said battery to the line at said outgoing repeater, a marginal relay in said tandem repeater, said relay operative responsive to the connection of said battery, a booster battery associated with said tandem repeater, means controlled by said relay for connecting said second battery for testing the class of station calling, and means for informing the operator of the call and the class to which the calling station belongs.

12. In a telephone system, a plurality of subscribers' stations some of which have restricted service attachments, a tandem repeater having a line relay, an outgoing special service repeater having a line relay, means for extending any line when calling to said tandem repeater and thence to said outgoing repeater and an associated operator's position, means whereby said outgoing repeater causes said tandem repeater to test for the presence of one of said attachments, means whereby the attachment, if present at the calling station, shunts out said tandem repeater relay which in turn shunts out said outgoing repeater relay, and means responsive to the shunting out of said outgoing repeater relay for reversing the direction of

signaling current and giving the operator a characteristic signal indicative of the class of station.

13. In a telephone system, a plurality of subscribers' stations some of which have restricted service attachments, a tandem repeater having a line relay, an outgoing special service repeater having a line relay, means for extending any line when calling to said tandem repeater and thence to said outgoing repeater and an associated operator's position, means whereby said outgoing repeater causes said tandem repeater to test for the presence of one of said attachments, means whereby said tandem repeater relay is shunted out or not depending upon the presence or absence of said attachment, means whereby said outgoing repeater relay is shunted out or not depending upon whether said tandem repeater relay is shunted out or not, and means controlled by said outgoing repeater relay for giving the operator a characteristic signal indicative of the class of station.
14. In a telephone system, means for extending a calling line to an operator's position, an automatic device at the exchange operated responsive to the completion of said connection, a device at the calling substation controlled by said first device, another device at the exchange controlled by said substation device to signal the operator, a repeater included in the connection between said line and the operator's position, inductive connections in the talking circuit at said repeater, and means in said repeater for relaying characteristic circuit conditions past said inductive connections to control said devices as set forth.
15. In a telephone system, a party line including restricted and unrestricted stations, an operator's switchboard, a trunk comprising incoming and outgoing inductively coupled sections, the outgoing section terminating at the switchboard, means whereby a party at any station on the line may set up a connection to the incoming section of the trunk, means at the point where the two sections are coupled, controlled over the outgoing section for testing the line to determine whether the connection was set up from a restricted or an unrestricted station, and means at the coupling point for transmitting the results of the test over the trunk section extending to the switchboard.

16. In a telephone system, a restricted and an unrestricted station, a trunk having inductively coupled incoming and outgoing sections, means for setting up a connection from either station to the incoming section, means controlled over the outgoing section for determining whether the station connected to the incoming section is restricted or unrestricted, and means controlled over the incoming section for transmitting the result of the test over the outgoing section.

17. In a telephone system, a restricted and an unrestricted station, a trunk having inductively coupled incoming and outgoing sections, means for setting up a connection from either station to the incoming section, an operator's switchboard, means for setting up a connection from the outgoing section to the switchboard, means controlled over the outgoing section for determining whether the station connected to the incoming section is restricted or unrestricted, and means controlled over the incoming section for transmitting the result of the test over the outgoing section.

In witness whereof, I hereunto subscribe my name this 12th day of November, A. D., 1923.

JOHN E. OSTLINE.
